UNITED STATES PATENT OFFICE.

LANSING ONDERDONK, OF NEW YORK, N. Y., ASSIGNOR TO UNION SPECIAL MACHINE COMPANY, OF CHICAGO, ILLINOIS, A CORPORATION OF ILLINOIS.

BLINDSTITCH SEWING-MACHINE.

1,132,680.

Specification of Letters Patent.

Patented Mar. 23, 1915.

Application filed December 6, 1907. Serial No. 405,357.

To all whom it may concern:

Be it known that I, LANSING ONDERDONK, a citizen of the United States, residing at New York city, in the county of New York, State of New York, have invented certain new and useful Improvements in Blindstitch Sewing-Machines, of which the following is a description, reference being had to the accompanying drawing and to the letters and figures of reference marked thereon.

My invention relates to new and useful improvements in blind stitch sewing machines, and has for its object to provide a feeding mechanism which shall be efficient in operation.

A further object of my invention is to provide means for raising and lowering the work supporting member and for adjusting the normal operative position of the same.

Still further objects of my invention will in part be obvious and will in part be hereinafter more fully disclosed.

In the drawings which show by way of illustration one embodiment of my invention: Figure 1 is a front view partly in section, of a sewing machine provided with my improvements. Fig. 2 is a sectional view showing the feed disk and the members for operating the same. Fig. 3 is a horizontal sectional view showing the toggle links for controlling the work support. Fig. 4 is a detail view showing the feed shaft and the friction feed therefor.

The base 1 has rising therefrom the usual standard 2, carrying an overhanging arm 3 at the forward end of which is the needle head 4. The needle 5 is carried by a needle lever 6 pivoted at 7 to the overhanging arm. Said needle lever receives its oscillation through a link 8, which is pivoted to a rock lever 9, mounted on the standard of the machine. Said rock shaft 9 receives its oscillation from an eccentric 10 on the main shaft 11, through a rod or pitman 12. The main shaft 11 is rotated by the usual belt wheel 13. The complementary stitch forming mechanism coöoperating with the needle has been omitted from the drawings for the sake of clearness, and for the reason that it forms no part of the invention. The base 1 has a work supporting arm 14, extending through an opening 15 in the standard and pivoted therein by a pivot bolt 16.

The feed shaft 17 is mounted in bearings

18 and 19 formed in the work supporting arm. Said feed shaft 17 carries a feed wheel 20 at its outer end, which extends through an opening formed in the work supporting arm. Said feed wheel 20 is provided with an intermediate crimping ridge 21, and with feed teeth 22 and 23 located upon opposite sides of the crimping ridge 21. The feed shaft 17 carries a clamping ring or flange 24, at its inner end. Said feed shaft also carries a central stud 25 on which is loosely mounted a collar 26, see Fig. 4. Said collar 26 has an arm 27 rigidly secured thereto and as said arm 27 is oscillated, said collar 26 will also be oscillated about the stud 25. Said collar 26 is also provided with outwardly extending short arms 28, 28, 28, which are disposed within the overhanging ring or flange 24.

The gripping plates 29, 29, 29, are each provided with a slot which engages over the ring or flange 24 and said slots are normally of such a width that the ring or flange will turn freely in the slots formed in the gripping plates. When, however, the gripping plates are slightly tilted, they will grip the ring or flange 24, and cause the same to move therewith. The gripping plates are seated at their inner end in recesses 30 formed in the collar 26.

The springs 31 are secured to the short arms 28 and bear against the gripping plate, normally tending to hold said gripping plates toward the short arms 28. When the collar 26 is turned in a clockwise direction, as viewed in Fig. 4, the gripping plates grip the flange or ring of the feed shaft, and move the same therewith. When however, the collar 26 is moved in the opposite direction, the springs allow the gripping plates to assume a position so that the gripping plates will slide freely on the ring or flange and the shaft will not be moved.

I have provided a bracket 32, which is secured to the overhanging arm, and a gripping plate 33 seated in said bracket, engages the flange or ring 24, and prevents movement of the feed shaft in the wrong direction. A spring 34 engages the clamping plate 33 and yields to allow the feed shaft to be turned in the proper direction. The arm 27 is oscillated by a link 35 which is pivoted to a stud adjustably secured in a segment slot formed in the arm 36. The

arm 36 is secured to a shaft 37 which is mounted in lugs 38 carried by the standard of the machine. The shaft 37 is oscillated by the arm 39, which is pivoted to a link 40. 5 The link 40 coöperates with an eccentric 41 mounted on the main shaft 11. As the main shaft rotates therefore, the feed shaft will be given an intermediate rotation which may be properly timed to present the material to the stitching mechanism. By adjusting the connection between the link 35 and the arm 36, I am thereby able to vary the length of the stitch. The material is held against the crimping ridge by the 15 presser members 42 and 43, which are pivoted to the overhanging arm, and yieldingly held in contact with the crimping ridge by means of the springs 44, 45.

The work supporting arm is provided 20 with the downwardly extending flange or lug 46. Said flange carries near its lower end a stud 47 having spaced ears between which is pivoted one end of the link 48. The link 48 in its opposite end is pivoted in 25 the bifurcated end of a link 49 by means of a pivot 50. The link 49 is rigidly secured to a shaft 51 which is mounted in a bearing 52 and carries on its outer end a hand lever 53. The bearing 52 is mounted in a slot 54 in the 30 standard, and is secured in place by a nut 55. The link 48 is also provided with a lip or lug 56 which contacts with the link 49 when the parts are in the position shown in Fig. 1. In this position the pivotal connection 50 between the links 48 and 49 is slightly above a line joining the pivotal connection of the link 48 with the stud 47, and the center of the shaft 51. The work supporting arm therefore will be held in its 40 raised position by the toggle links. When it is desired to adjust the position of the crimping ridge relative to the needle, the locking nut 55 is loosened and the adjusting screw 57 is turned. Said adjusting screw 57 is threaded at its inner end into a lug 58 carried by the bearing 52, and is provided at its outer end with a collar 59 which is held in a seat in the bed plate by means of a plate 60. It will be apparent therefore, 50 that as the adjusting screw 57 is turned in one direction, or the other, the front end of the work support will be raised or lowered.

By the arrangement above described, the work-supporting arm may be swung on its 55 pivot to lower or raise it to the proper height to adjust the crimping ridge with respect to the needle, and also to swing it to allow of insertion and removal of the work.

Having thus particularly described my 60 invention, what I claim as new and desire to secure by Letters Patent, is:—

1. The combination with an overhanging arm, of a needle carried thereby, a work supporting arm, means for raising and lowering said work supporting arm, and for holding

the same rigidly in raised position and means for adjusting the position of the work supporting arm relative to said needle.

2. The combination with an overhanging arm, a needle carried thereby, a work support, a crimping ridge carried thereby, means for raising and lowering said work support and holding the same rigidly in raised position and an adjusting screw for varying the position of said work support 75 relative to said needle.

3. The combination of a work supporting arm, a needle, means for supporting and operating the same, a toggle lever for raising and lowering said work supporting arm 80 relative to said needle, and means for adjusting the position of said toggle lever.

4. The combination with a standard, a needle supported by said standard, a work supporting arm pivoted to said standard 85 and movable relative to said needle, a link pivoted to said arm, a second link pivoted to said first named link and to the standard, and a lug for limiting the movement of said links and for holding the work supporting 90 arm in raised position.

5. The combination with a standard, a needle supported by said standard of a work supporting arm pivoted to said standard and movable relative to said needle, a link 95 pivoted to said arm, a second link pivoted to said first named link and to the standard and a lug for limiting the movement of said links and for holding the work supporting arm in raised position, and means for adjusting the position of the pivotal connection between the second link and the standard. 100

6. The combination with a standard, a needle supported by said standard, of a work 105 supporting arm pivoted to said standard and movable relative to said needle, a link pivoted to said arm, a second link pivoted to said first named link and to the standard, a lug for limiting the movement of said links 110 and for holding the work supporting arm in raised position, an adjusting screw mounted in said standard and engaging the pivot bearing of the second link whereby the position of the work supporting arm may be 115 adjusted.

7. The combination of a standard, a needle supported by said standard, a work supporting arm pivoted to said standard and movable relative to said needle, a link pivoted to said work supporting arm, a second link pivoted to said first link and to a shaft 120 mounted in a bearing carried by the standard and a hand lever connected to said shaft.

8. The combination of a standard, a needle supported by said standard, a work supporting arm pivoted to said standard and movable relative to said needle, a link pivoted to said work supporting arm, a second link pivoted to said first link and to a shaft 125 130

mounted in a bearing carried by the standard, and a hand lever connected to said shaft, an adjusting screw mounted in said standard and connected to the bearing carrying the shaft whereby the position of the work supporting arm may be varied.

9. The combination with a standard, of an overhanging arm carried thereby, a needle mounted on said overhanging arm, a work supporting arm pivoted to said standard, a crimping ridge carried by said work supporting arm, a toggle lever connected to said work supporting arm, a shaft connected to said toggle lever, an adjustable bearing for said shaft, a hand lever connected to said shaft and an adjusting screw for adjusting the position of said bearing.

10. The combination with an overhanging arm, of a needle carried thereby, a pivoted work supporting arm, means for raising and lowering said work supporting arm and for holding the same rigidly in raised position, said raising and lowering means being attached at a point away from the outer end

of the work supporting arm and means for adjusting the position of the work-supporting arm relative to the needle.

11. The combination of an overhanging arm, a needle carried thereby, said needle at the stitching point moving into and out of the material at points which are in substantially a horizontal line, a movable work support beneath the needle, means for raising and lowering the work support to permit the insertion of the material over the work support for engagement by the needle, and means coöperating with said raising and lowering means for positively moving said work support toward and from the needle to position the same relative to the needle when in normal operative relation to the needle.

In testimony whereof I affix my signature, in presence of two witnesses.
